UNITED STATES PATENT OFFICE

ROSA BINNER SCOGNAMILLO, OF NEW YORK, N. Y.

DESIGN FOR A CORSET

Application filed March 25, 1931. Serial No. 39,240. Term of patent 3½ years.

To all whom it may concern:

Be it known that I, ROSA BINNER SCOGNAMILLO, a citizen of the United States, residing at New York, in the county of New York and State of New York, have invented a new, original, and ornamental Design for a Corset, of which the following is a specification, reference being had to the accompanying drawings, forming part thereof.

Fig. 1 is a rear elevational view of a corset, showing my new design.

Fig. 2 is a front elevational view of the same.

I claim:

The ornamental design for a corset, as shown.

In testimony whereof I have affixed my signature.

ROSA BINNER SCOGNAMILLO.
